His ATTORNEY

UNITED STATES PATENT OFFICE.

JOHN T. STEINBAUGH, OF KANSAS CITY, KANSAS.

COLLAR-HOLDER.

1,299,255.

Specification of Letters Patent.

Patented Apr. 1, 1919.

Application filed June 11, 1917. Serial No. 173,926.

To all whom it may concern:

Be it known that I, JOHN T. STEINBAUGH, a citizen of the United States, residing at Kansas City, in the county of Wyandotte and State of Kansas, have invented a certain new and useful Improvement in Collar-Holders, of which the following is a specification.

My invention relates to improvements in collar holders.

It is particularly adapted for attaching the collar to the rear portion of the neck band of a shirt.

One of the objects of my invention is to provide a collar holder which will permit of the collar being quickly attached to the neck band, which will not interfere with the sliding of a tie in the collar, which has small transverse thickness, which may be quickly attached to a collar and which is attractive in appearance and cheap to manufacture.

The novel features of my invention are hereinafter fully described and claimed.

In the accompanying drawing which illustrates my invention.

Figure 1 is a perspective view, enlarged, of my improved collar holder as constructed of sheet metal.

Fig. 2 is an elevation of the same, shown applied to a collar, the rear portion only of which is shown.

Fig. 3 is an edge view of the collar holder shown in Figs. 1 and 2, shown partly engaged with a collar, the latter being shown in vertical section.

Fig. 4 is an edge elevation of a collar holder shown in the preceding figures, shown engaged with a collar and the neck band of a shirt, the collar and neck band being shown in vertical section.

Fig. 5 is a front elevation of a modified form of my invention, as constructed of resilient wire.

Fig. 6 is an edge elevation of the collar holder shown in Fig. 5.

Similar reference characters designate similar parts in the different views.

In the form of my invention shown in Figs. 1 to 4, the collar holder is made of flat material, preferably sheet metal of considerable resiliency, such as German silver, brass, silver, or other suitable material.

Broadly stated, my improved collar holder comprises a body having two reversely disposed transverse bends, one above the other, and having two arms, one of which extends

from the lower bend above the upper bend, and the other arm extending from the upper bend so as to project below the lower bend. I will now describe the form of my invention shown in Figs. 1 to 4.

The collar holder comprises a U-shaped body portion having one relatively long arm 1 adapted to be slipped under the rear flap 2 of a neck band 3 of a shirt, as shown in Fig. 4. The other arm 4 of the body portion, at its upper end is extended laterally outwardly and then downwardly to form a hook 5 which is adapted to be inserted through a button-hole 6 in the rear side of a collar 7.

The hook 5 and arm 4 preferably converge downwardly toward each other, so that, when the collar holder is in the operative position shown in Fig. 4, the collar will be clamped between the hook 5 and the arm 4, the convergence of the parts being such that this function will be effected.

In order that the collar holder may be easily and quickly inserted through the button-hole 6, the hook 5 projects below the bottom of the U or portions connecting the arms 1 and 4 of the body. Such projection of the hook 5 enables the wearer to easily start the hook through the button-hole, which would not be the case if the hook did not extend below the body portion of the holder.

In order that no difficulty may be encountered in inserting the hook in proper position, the arm 4 has its upper end terminating at the upper end of the hook. There is, thus, no upwardly extending portion on the arm 4 above the hook which would, if present, interfere with the ready insertion of the hook in operative position.

The arm 1 extends a considerable distance above the arm 4, thus enabling the holder to be readily and securely held between the thumb and forefinger, while the hook 5 is being inserted in the button-hole. This arm 1, as already described, serves to engage the flap of the neck band, and it also serves, when the neck band is of light flimsy material having little stiffness, to reinforce and support the neck band.

In the operation of my invention, the hook 5 is slipped through the button-hole 6 to the position shown in Fig. 4, in which position the collar 7 will be clamped between the arm 4 and the hook 5, the hook and arm being spread apart by the collar. Preferably the projecting lower end of the arm 5

is rounded, as shown, which permits it to be easily forced through a button-hole which has been closed during the ironing operation.

The upper end of the hook will extend 5 through the button-hole and hold the holder from slipping upwardly. To attach the collar to the shirt, it is but necessary to slip the arm 1 under the flap 2 of the neck band 3. The collar may then be buttoned at its 10 ends to the front of the shirt in the usual manner.

The collar will then be securely held to the shirt, and a tie 8, shown in Fig. 4, may then be slipped lengthwise between the folds of 15 the collar without any interference by the collar holder. The latter has relatively small transverse thickness, so that it does not cause any pressure against the neck of the wearer, nor does it bulge outwardly the 20 back fold of the collar.

The form of my invention shown in Figs. 5 and 6, is composed of wire, preferably resilient. It has the same general shape as the form shown in Figs. 1 to 4. It has a U- 25 shaped body portion having an arm 9 of inverted U-shape, which corresponds in function and location to the arm 1. The two wire portions 10, forming the other part of the U-shaped body portion, are extended 30 outwardly and laterally and thence downwardly to form two hooks 11 which project below the lower end of the U-shaped body portion and which have their lower portions

upwardly turned. The hooks 11 perform the function of the hook 5 and are insertible 35 through the button-hole of the collar in the same manner as the latter.

With the use of my invention, if the button-hole in the rear portion of the collar should happen to be at one side of the proper 40 central position, the collar, nevertheless, will upon being buttoned, at the front, assume its proper position, the collar holder permitting this by reason of its slidable connection with the flap of the neck band of the shirt. 45

I do not limit my invention to the structures shown and described, as other modifications, within the scope of the appended 50 claim, may be made without departing from the spirit of my invention.

What I claim is:—

A collar holder comprising a body having two reversely disposed transverse bends, one above the other, a vertical portion intermediate of said bends, and two arms, one of 55 which extends upwardly from the lower bend and terminates above the upper bend, the other arm extending downwardly from the upper bend, inclining toward the intermediate portion, and terminating below the 60 lower bend, the intermediate portion and the arms being in different planes.

In testimony whereof I have signed my name to this specification.

JOHN T. STEINBAUGH.
